(57) **CLAIM**

I claim the ornamental design for an LED spot lamp lens, as shown and described.

DESCRIPTION

FIG. 1 is a front perspective view of a design of the LED spot lamp lens;

FIG. 2 is a left side perspective view of the LED spot lamp lens of FIG. 1;

FIG. 3 is a front elevation view of the LED spot lamp lens of FIG. 1;

FIG. 4 is a top plan view of the LED spot lamp lens of FIG. 1;

FIG. 5 is a bottom plan view of the LED spot lamp lens of FIG. 1;

FIG. 6 is a right side elevation view of the LED spot lamp lens of FIG. 1; and,

FIG. 7 is a left side elevation view of the LED spot lamp lens of FIG. 1.

The features shown in broken lines depict environmental subject matter only and form no part of the claimed design. The back side of the LED spot lamp lens forms no part of the design.
